(57) **CLAIM**

An ornamental design for a grill, as shown and described.

DESCRIPTION

FIG. 1 is a first perspective view of the grill, according to the present invention;

FIG. 2 is a front elevational view of the grill shown in FIG. 1;

FIG. 3 is a rear elevational view of the grill shown in FIG. 1;

FIG. 4 is a top plan view of the grill shown in FIG. 1;

FIG. 5 is a bottom plan view of the grill shown in FIG. 1;

FIG. 6 is a first side elevational view of the grill shown in FIG. 1;

FIG. 7 is a second side elevational view of the grill shown in FIG. 1;

FIG. 8 is a second perspective view of the grill shown in FIG. 1;

FIG. 9 is a third perspective view of the grill shown in FIG. 1; and,

FIG. 10 is a fourth perspective view of the grill shown in FIG. 1.

In the drawings, the broken lines represent portions of the

grill that form no part of the claimed design.

1 Claim, 10 Drawing Sheets
